UNITED STATES PATENT AND TRADEMARK OFFICE
Certificate

Patent No. D413,462

Patented: September 7, 1999

On petition requesting issuance of a certificate for correction of inventorship pursuant to 35 U.S.C. 256, it has been found that the above identified patent, through error and without deceptive intent, improperly sets forth the inventorship.

Accordingly, it is hereby certified that the correct inventorship of this patent is: Michael John Paus, High Point, NC; and Alexander Julian, Ridgefield, CT.

Signed and Sealed this Sixteenth Day of July 2002.
